UNITED STATES PATENT OFFICE.

ALBERT S. ENGLISH, OF ANACONDA, MONTANA.

TRAIN-PIPE COUPLING.

1,106,354.

Specification of Letters Patent.

Patented Aug. 4, 1914.

Application filed January 21, 1914. Serial No. 813,510.

To all whom it may concern:

Be it known that I, ALBERT S. ENGLISH, a citizen of the United States, residing at Anaconda, in the county of Deerlodge and 5 State of Montana, have invented a new and useful Train-Pipe Coupling, of which the following is a specification.

This invention relates to improvements in train pipe couplings.

10 An object of the present invention is to provide a train pipe coupling which will automatically couple and uncouple the pipes of successive and adjoining cars of a train.

15 A further object is to provide an automatic coupling which will remain tight against leaks while the cars are rounding a curve and which will allow for the rocking and jouncing of the cars.

20 A further object is to provide a coupling which will be simple in construction and thus cheap to manufacture and which will at the same time be practical and efficient in use.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

35 In the drawings accompanying this specification and forming a part thereof, the preferred form of my invention is illustrated, in which:

Figure 1 is a side view in elevation of my improved train pipe coupling. Fig. 2 is a 40 view taken on the line A—A of Fig. 1. Fig. 3 is a sectional view of a portion of the coupling member. Fig. 4 is a detail view of a portion of the plunger and the valve ball.

45 Referring to the drawings in which similar reference numerals designate corresponding parts throughout the several views, 5—5 represent two similar chambers which communicate through the cross pipe 6 and which latter is in communication with a pipe 7 which is to be coupled to a similar pipe disposed upon an adjacent car. Each car will be provided at each end with a coupling apparatus as illustrated in Fig. 2, and each of the said coupling devices includes two parts 50 so that the various cars may be coupled in-

discriminately and without regard to any fixed relation of the same.

The chambers or casings 5 which are identical, are each provided with the cover 8 which extends nearly the entire length of 60 the casing and is substantially semi-circular in cross section and which is secured to and effects a tight joint with an outstanding flange 9. Each chamber is provided intermediate its ends with a partition 10 extending thereacross and into which fits the ball valve member 11 which is provided with the bore 12 extending therethrough and through which the plunger 13 slidably extends.

65 The plunger in question is composed of 70 two parts, the front and rear sections 13 and 14 which are provided with the abutting threaded ends 15 which are secured in alignment and held together by an outstanding flanged coupling 16 to which they are 75 threaded secured. The plunger is provided with the bore 17 extending therethrough and by means of which the air or steam is conducted through the coupling to the adjacent coupling which is in communication therewith. In order to maintain the plunger in an extended position, the tension springs 18 are provided and are fixedly secured to the flanged coupling 16 and to the front wall 19 of the casing 5. The casing 5 80 is formed into two non-communicating compartments by the partition 10 and the plunger extends through the ball-like valve 11 and projects into the rear compartment 20 and is prevented from moving therefrom 90 by the outstanding integral flange 21 which is formed upon the extremity of the plunger. The plunger is provided with a plurality of openings 22 extending through the side walls thereof which when they come into communication with the rear compartment 20 95 allows the air or steam to flow into the plunger and therethrough.

95 The extreme ends of the plungers are formed one with a ball-like end 23 and the 100 other with the receiving socket 24. Thus the ball and socket ends of the two plungers of a single coupling device will register and receive the corresponding socket and ball-like ends of the adjacent coupling device of the next adjacent car.

105 With the foregoing coupling device, a tight and efficient joint will be had between the couplings of two cars and the rounding of a curve will not in any way destroy the 110

tight union therebetween. The ball and socket joint will at all times effect a tight union between the meeting plungers. Also the manner in which the plungers are connected together, allows for the rocking and side play of the cars. When the plungers are extended by the springs 18 the plungers will be automatically cut off from and out of communication with the rear chamber 20 and therefore with the pipe 7 as it is thought will be readily apparent from a reference to the drawings.

Having thus fully described my invention, what I claim is:—

- 15 1. A pipe coupling apparatus comprising a pair of similar casings, means extending across the ends thereof holding the same in spaced relation, partitions extending across the casing intermediate the ends thereof, a ball with a bore extending therethrough positioned within said partitions, pipe-like plungers extending through said ball bores and extending into the rear compartments defined by the partitions, supply pipes communicating with said rear compartments, said plungers provided with closed inner ends and with apertures extending through the side walls thereof, said apertures effecting a valve action with the said balls, a 20 flange carried by said plungers intermediate their ends and housed within said casings, resilient means engaging said flange and the walls of said casings adapted to hold the plungers in extended position, and means 25 carried by the extremities of said plungers adapted to effect a tight juncture with the meeting extremities of a second pair of similar plungers.
- 30 2. A coupling apparatus comprising an integral frame with spaced parallel casings, partitions extending across the said casings intermediate their ends and dividing the same into front and rear compartments, supply pipes communicating with the said rear

compartments, spherical valve members 45 positioned within said partitions and provided with bores extending therethrough, sectional pipe-like plungers slidably mounted within said spherical valve members bores, said plungers provided with apertures 50 extending through the side walls and effecting a valve action with the said spherical valve members, a flanged coupling connecting the sections of said plungers, a plurality of tension springs engaging the front walls 55 of said casings and the said flanged couplings adapted to hold said plungers in extended position, and means carried by the ends of said plungers for effecting a tight juncture with the meeting extremities of a 60 second pair of plungers.

3. A pipe coupling comprising a casing, a partition extending across the casing intermediate the ends thereof, a ball with a bore extending therethrough positioned within 65 said partition, a pipe-like plunger extending through said ball bore and extending into the rear compartment defined by the partition, a supply pipe communicating with said rear compartment, said plunger provided 70 with a closed rear end and with an aperture extending through the side wall thereof, said aperture effecting a valve action with said bore, resilient means engaging the pipe-like plunger and the wall of said casing, 75 adapted to hold said plunger in an extended position, and means carried by the extremity of said plunger adapted to effect a tight juncture with the meeting extremity of a second and oppositely arranged plunger. 80

In testimony that I claim the foregoing as my own, I have hereto affixed my signature in the presence of two witnesses.

ALBERT S. ENGLISH.
